CLAIM

The ornamental design for a shaving razor holding
device, as shown and described.

DESCRIPTION

FIG. 1 is a front elevational view of a shaving razor
holding device showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a cross-sectional view taken along line 7—7 of
FIG. 2.
